UNITED STATES PATENT OFFICE

135,662

DESIGN FOR A NAIL OR SIMILAR ARTICLE

Edmond C. Matignon, Oakland, Calif.

Application February 19, 1943, Serial No. 109,582

Term of patent 14 years

To all whom it may concern:

Be it known that I, Edmond C. Matignon, a citizen of the United States residing at Oakland, county of Alameda, and State of California, have invented a new, original, and ornamental Design for a Nail or Similar Article, of which the following is a specification.

In the drawing, Fig. 1 is an elevational view of one side of the nail, showing my new design, both sides thereof being identical in appearance.

Fig. 2 is an end view of the head end of the nail of Fig. 1.

I claim:

The ornamental design for a nail or similar article, as shown.

EDMOND C. MATIGNON.
